UNITED STATES PATENT OFFICE.

LONNIE THOMAS PENNY, OF RALEIGH, NORTH CAROLINA.

SIGNAL.

1,377,520.

Specification of Letters Patent. Patented May 10, 1921.

Application filed October 4, 1918. Serial No. 256,854.

To all whom it may concern:

Be it known that I, LONNIE T. PENNY, a citizen of the United States, residing at Raleigh, in the county of Wake and State 5 of North Carolina, have invented certain new and useful Improvements in Signals, of which the following is a specification.

The present invention relates to signals, and particularly to that type which may be 10 operated by fluid pressure to sound a whistle or actuate some other suitable signal device.

The object of this invention is to provide a signal which may be used on trains and 15 preferably attached to the usual air brake train line for establishing means of communication from end to end of the train, particularly when the ends of the train are not visible one to the other, such as when the 20 train is on a curve, at night, and under various other kindred circumstances; a signal which may be easily tapped into the train line at any desired point and actuated by the slight reduction in the normal pressure 25 therein; and a signal which may be used both in the engine and in the caboose, and by means of which the conductor on the rear end of the train may signal the engineer and the latter acknowledge the signal 30 without the crew being visible to each other.

Another object of the invention is to provide a signal device of this character which comprises relatively few parts, is positive in operation, which is compact and occupies 35 but small space, which requires no adjustment, which can be installed with but slight alterations and cannot easily get out of order. The above, and various other more or less important objects and advantages 40 of this invention will be in part understood from, and in part set forth in, the following detailed description of the present preferred embodiment, the same being illustrated in the accompanying drawings, 45 wherein:

Figure 1 is a diagrammatic view of a train line pipe of the usual air brake system, and two signals constructed according to this invention tapped into the pipe at different points.

Fig. 2 is an enlarged view, partly in section, of the signal apparatus with parts broken away.

Fig. 3 is a detail sectional view of the

whistle valve and the parts immediately 55 adjacent thereto.

Fig. 4 is a transverse section taken on the line 4—4 of Fig. 3, and looking in the direction of the whistle as shown by the arrows. 60

Fig. 5 is a similar view taken on the line 5—5 of Fig. 3 through the connection beyond the valve and looking toward the same as indicated by the arrows.

Fig. 6 is a transverse section through the 65 controlling cylinder, taken on the line 6—6 of Fig. 2 adjacent to and looking away from the whistle.

Fig. 7 is a similar view taken on the line 7—7 of Fig. 2 near the train pipe connection 70 and looking toward the same, and

Fig. 8 is a detail sectional view through the check valve controlling the passage of air between the main cylinder and the reservoir. 75

The apparatus of this invention is designed particularly for application to the train line pipe of freight and other trains, but may be used wherever a pipe line is adapted to be normally maintained under 80 pressure and adapted to be vented to effect a reduction of the pressure in the line, the present signal apparatus being normally held inoperative by pressure and actuated by a reduction in such normal pressure. 85

Referring to the accompanying drawings, illustrating the invention as applied to train line pipe of the ordinary air brake system, 10 designates the train line pipe which is shown diagrammatically in sections representing cars of a train of desired length and with suitable pipe line couplings 11 of usual form. 90

Each signal apparatus comprises a main cylinder 12 closed at opposite ends by heads 95 13 and 14 and connected to the pipe line 10, through a port 15 in the head 14, by a coupling pipe 16. The pipe 16 is threaded into the head 14 at one end and may be tapped in any suitable manner into the train pipe 10 100 for establishing communication between the train line pipe and the cylinder 12. The head 14 is provided with a second port 17 from which leads a supply pipe 18, the latter having a check valve therein as shown in 105 detail in Fig. 8 of the drawings. The check valve comprises the spaced heads 19 and 20 into which are secured the opposite ends of

the body 21 of the valve. The valve head 22 is seated against the end of the body 21 within the head 19, and has a stem 23 projecting through the body and supporting 5 therein a spring 24 seated within said end of the body and bearing at its other end against a shoulder 25 on the free end of the stem. The valve 22 is remote from the cylinder head 14, and the spring 24 normally urges the valve to its seat against the pressure in the cylinder.

The supply pipe 18, leading from the check valve, opens into a tank or reservoir 26 adapted to maintain a reserve fluid supply 15 for blowing a whistle 27. The tank 26 is connected by a pipe 28 to the main cylinder 12 through the head 13. The whistle 27, being any approved type of air whistle, is connected by a pipe or elbow 29 to the head 20 13, a whistle valve being interposed in the pipe.

As shown in Figs. 2 and 3, the valve for the whistle comprises a casing 30 having one end threaded into the head 13 and a 25 valve seat in such end. The other end of the casing 30 is threaded into the pipe 29. A valve 31 is seated against the end of the casing having the seat, and is provided with a stem 32 non-circular in cross section and 30 fitted in a circular bore in the casing for guiding the stem and valve in movement. The outer end of the casing 30 is counter-bored to receive a spring 33 which surrounds the stem 32, the spring bearing at 35 one end against the casing and at its other end against a shoulder 34 on the outer end of the stem to normally seat the valve 31. The stem 32 of the valve has a projection 35 extending into the cylinder 12 and provided with a head 36.

Within the cylinder 12 is mounted a double piston 37, the heads or sections of which are connected together in suitably spaced relation by a neck 38. The pistons 37 are seated in the cylinder by packing rings in the usual manner. The end of the piston 37 adjacent the head 14 has a stem 39 upon which is mounted a spring 40 bearing at one end against the piston 37 and seated at its 50 other end against a shoulder 41 formed in the bore 42 of the head 14. The stem 39 is adapted to move into the bore 42 when the piston is moved toward the head 14. The other end of the piston 37 carries a coupling member 43 in the form of a stem threaded into the end of the piston and provided with a pair of opposed outstanding fingers having their outer ends extending toward each other in overhanging relation to engage about and behind the head 36 of the whistle valve, and adapted to engage and disengage the same by a relative lateral shifting of the coupling member 43 and the head 36. The heads 13 and 14 are 55 detachably mounted upon the opposite ends

of the cylinder 12, and the parts within the cylinder may therefore be easily removed and assembled.

In use, one or more signal apparatus as above described may be tapped into the 70 train line pipe 10, such as one near the engineer and another in the caboose or on the rear car of the train. The normal train pipe line pressure is seventy pounds, and this pressure is conducted through the pipe 75 16 to the cylinder 12 and against the adjacent end of the piston 37, urging the latter toward the whistle and closing the valve thereof. The spring 40 assists in maintaining the piston 37 in this shifted position. 80 The pressure passing through the adjacent end of the cylinder 12 from the pipe 16, is conducted through the check valve, designated by its body 21, and through the pipe 85 18 into the reservoir 26, where a reserve pressure is maintained. As the pipe 28 connects the tank 26 with the other or outer end of the cylinder 12, the pressure is equalized on opposite sides of the piston, the spring 40 however holding the whistle valve 90 closed.

As soon as there is a reduction in the train pipe line 10, the pressure is reduced in the near end of the cylinder and the pressure from the tank 26 shifts the piston 37 against the spring 40 and the coupling member 43 draws the whistle valve 31 into open position. The pressure is now relieved through the whistle, sounding the same and permitting the spring 40 to work and close 95 the whistle valve 31. If the pressure in the train pipe line 10 is still maintained reduced, the piston 37 is thus vibrated continuously and intermittently sounds the whistle until the pressure in the reservoir 100 26 is lowered to that in the train pipe line 10.

The apparatus of this invention, being thus constructed and mounted in the pipe line is susceptible of slight variation in the 110 train pipe line pressure and may be actuated without appreciably affecting the brake mechanism.

What is claimed is:

1. In signal apparatus, the combination 115 with a fluid pressure train pipe, of a fluid actuated signal element, and means interposed between the element and the train pipe for normally maintaining the element inoperative and adapted to be actuated upon a reduction of the pressure in the train pipe at normal train pipe pressure, said means consisting of a cylinder, a head on one end of said cylinder having a valve seat, a head on the other end of said cylinder formed with a pair of ports and a boss formed with a bore, a spring mounted in said bore, a double piston in said cylinder, a stem projecting from the outer end of one of said pistons and fitting in said spring and bore, 120 125 130

and a coupling projecting from the outer end of the other piston to engage the valve of said signal element.

2. In signal apparatus, the combination of a cylinder adapted for connection at one end to a fluid pressure line, a pressure actuated signal device connected to the other end of the cylinder, a shiftable member sealed in the cylinder between the ends thereof and consisting of twin connected pistons, a coupling formed on one of said pistons and a stem formed on the other piston, means intercommunicating the ends of the cylinder to equalize the pressure at opposite sides of the shiftable member, and a valve for the signal device connected positively by the coupling of one of the pistons to the shiftable member and adapted to be opened thereby upon the movement of the member incident to the reduction in the fluid pressure line.

3. In signal apparatus, the combination of a cylinder adapted for communication at opposite ends with a fluid pressure line, a whistle connected to one end of the cylinder, a valve for opening the whistle to the cylinder, the stem of said valve being formed with a head and a shiftable member sealed in the cylinder having a coupling to engage said head on the valve stem, normally urged toward the whistle and adapted to be shifted by reduction in the fluid pressure line from the whistle and having connection with the valve to open the same.

35 4. In signal apparatus, the combination of a cylinder adapted for communication at opposite ends with a fluid pressure line, a whistle connected to one end of the cylinder, a valve for opening the whistle to the cylinder, a spring around the stem of said valve, a head formed on the end of said stem, a shiftable member sealed in the cylinder, a coupling carried by said member to connect with the head on the valve stem, said shiftable member being normally urged toward the whistle, and a fluid pressure storage tank connected between the ends of the cylinder for maintaining pressure against the shiftable member and moving the same to open the whistle valve upon the reduction in the fluid pressure line.

5. In signal apparatus, the combination of a cylinder, a pipe connecting one end of the cylinder to a fluid pressure line, a storage tank connected to said end of the cylinder, a pipe leading from the tank to the other end of the cylinder, a whistle connected to the other end of the cylinder, a valve between the cylinder and the whistle, a spring around the stem of said valve, a head formed on the projected end of said stem, and a shiftable member in the cylinder sealed between the ends thereof and normally urged toward the valve, a coupling on said member to engage the head on the valve

stem to maintain the valve closed, said member being adapted to be moved by pressure in said tank upon the reduction of pressure in the fluid pressure line for opening the valve and sounding the whistle.

70

6. In signal apparatus, the combination of a cylinder adapted for connection with a fluid pressure line, a fluid actuated signal element connected to the cylinder and including a controlling valve, a spring around the stem of said valve, a projected end on said stem formed with a head, a shiftable member in the cylinder, a coupling carried by said member and engaging the head of the valve stem connected to the valve and normally urged for movement in a direction to close the valve, and a by-pass line between the ends of the cylinder adapted to equalize pressure on opposite sides of the said member and to shift the member upon a reduction in the fluid pressure line for opening the signal valve.

75

7. In signal apparatus, the combination of a cylinder, a pipe leading from one end of the cylinder and adapted to be connected to a fluid pressure line, a reservoir, a pipe connecting said end of the cylinder to the reservoir and including a check valve adapted to open toward the reservoir, a pipe between the reservoir and the other end of the cylinder for equalizing the pressure in the opposite ends of the cylinder, a whistle connected to said other end of the cylinder and including a controlling valve adapted to be normally seated for closing the whistle to the cylinder, a piston in the cylinder, a spring in said first end of the cylinder engaging the piston for urging the same toward the whistle valve, said piston being adapted to be moved against the pressure of the spring upon the reduction in pressure in the fluid pressure line by the fluid pressure in the reservoir, and a connection between the whistle valve and the piston for opening the whistle when the piston is moved, said connection consisting of a head on the stem of the whistle valve and a coupling on said piston to make positive connection with the said head of the valve stem.

90

8. In signal apparatus, the combination of a cylinder, means for connecting the cylinder to a fluid pressure line, a piston in the cylinder adapted to receive the fluid pressure thereagainst, a spring in the cylinder engaging the piston to augment the fluid pressure and urge the piston for movement in one direction, a by-pass around the piston to equalize pressure at opposite sides of the piston, and a whistle connected to the cylinder remote from the fluid pressure line and including a valve connected to the piston and adapted to be normally closed thereby, the piston being adapted to be moved upon a reduction in the fluid pres-

105

sure line to open the valve, said valve when open being adapted to reduce the pressure at the remote side of the piston and the spring being adapted to return the piston upon the equalization of the reduced pressure for intermittently sounding the whistle, said connection between the whistle valve and piston, consisting of a head formed on one end of the stem of said whistle valve

and a coupling carried by the piston and engaging said head.

In testimony whereof I affix my signature in presence of two witnesses.

LONNIE THOMAS PENNY.
